OTHER PUBLICATIONS

U.S. Appl. No. 29/422,430, filed on May 21, 2012, including 2 pages of specification and 42 pages of drawing sheets.

Primary Examiner — Susan Bennett Hattan*Assistant Examiner* — Janice Hallmark(74) *Attorney, Agent, or Firm* — Oblon, Spivak, McClelland, Maier & Neustadt, L.L.P.(57) **CLAIM**

The ornamental design for a hand-held aerosol generator, as shown and described.

DESCRIPTION

FIG. 1 is a perspective view of a hand-held aerosol generator showing our new design as viewed from the right side of the page;

FIG. 2 is a side elevational view of one side thereof;

FIG. 3 is a top plan view thereof;

FIG. 4 is a side elevational view of the opposite side thereof;

FIG. 5 is a bottom plan view thereof;

FIG. 6 is a front plan view thereof; and,

FIG. 7 is a rear plan view thereof.

1 Claim, 4 Drawing Sheets(56)
